UNITED STATES PATENT OFFICE

2,568,362

GARDEN AND BEACH UMBRELLA

Vincent A. R. Primavera, Norton, Conn.

Application November 8, 1948, Serial No. 58,820

6 Claims. (Cl. 135—20)

1

My invention relates to umbrellas of that big type which is known under the name "garden and beach umbrellas."

The awning of such an umbrella is spread and tightly stretched by sliding a collar upwardly along the umbrella stick until this collar snaps over a stop resiliently projecting from a recess of the stick. In order to fold the umbrella again, this stop must be pressed into this recess while simultaneously the collar is moved vertically. These operations require large forces due to the large weight and the strong tension of a big awning. In addition, these operations are difficult and tiresome because the stop to be pressed is situated high near the upper end of the stick where it is not easily accessible.

Objects of my invention are to facilitate the operation of a garden and beach umbrella, to provide the umbrella with a chain or with a similarly flexible element which can be pulled or relaxed conveniently, to hoist or lower the collar and thereby to spread or fold the awning by such pull or relaxation, and to operate the stop by the same flexible element whereby one hand can perform all necessary operations.

Other objects are to guide this flexible element so that it can be operated in a convenient direction, to hoist the collar by downward movement whereby the own weight of the operator is available for pulling said element, and to press the stop out of the stopping position by lateral movement of the flexible element whereby the latter operation does not interfere with simultaneous pull or relaxation of this element in longitudinal direction.

Further objects are to reduce the force necessary for spreading and stretching, to exert a relatively large stretching and hoisting force by application of a relatively small hand force, and to provide an umbrella of heavy weight and large measures with means to stretch its awning tightly.

Still other objects are to attain these results with simple and reliably operating means, and to provide a garden and beach umbrella that can be inexpensively made and can be easily maintained in good working condition.

Still other objects and advantages will appear from the following description of exemplifying embodiments of my invention, from the appended claims and from the accompanying drawing in which:

Fig. 1 shows a side view of an illustrative embodiment of my invention, a portion of the umbrella's awning being broken off.

2

Fig. 2 shows a side view of a broken off portion of the same embodiment.

Fig. 3 shows another side view of the portion shown in Fig. 2, Fig. 3 being seen from the right side in Fig. 2.

Figs. 4 and 5 show side views of a modified portion of the same embodiment, Fig. 4 corresponding to Fig. 2 and Fig. 5 corresponding to Fig. 3.

10 Fig. 6 shows a cross-section taken along the line 6—6 in Fig. 3.

Fig. 7 shows a cross-section taken along the line 7—7 in Fig. 5.

15 Fig. 1 is represented on a scale much more reduced than the scale of the remaining figures.

Referring to the drawing, numeral 1 indicates a foldable cover or awning which is supported by a stick 2. This stick is vertically erected on the ground and may, for example, pass 20 through a table 3. The awning 1 can be spread and tightly stretched by arms 4 hinged in well known manner to a collar 5 which surrounds the stick 2. This collar is slidable along the stick 2 and, moving upwardly, snaps over a nose 25 8 which forms a stop against downward movement of the collar. The stop 8 is of a structure well known in the art of umbrellas. This structure provides a resilient connection of the stop with the stick whereby the stop is urged into the 30 stopping position shown in the drawing. In this position, the stop 8 projects laterally beyond the stick 2. The stop 2 can be removed from this stopping position by pressing the stop toward the axis of the stick into a lateral recess 9 of the latter.

35 According to my invention, this pressure is exerted by a member 11 or 21 which is so hinged to an extension 12 of the collar 5 that this member contacts the stop 8 in the direction of the stop removing pressure when the collar is positioned over the stop. The member can be moved in this direction by lateral movement of a chain-like flexible element 15 or 25 which engages the member in suitable manner, for example, by 40 passing through a vertical opening 13 of the member.

The member 11 shown in Figs. 1, 2, 3 and 6 has a fork-shaped part 14 contacting the stop 8 and movable in a substantially lateral or horizontal direction. The member 11 presses the stop 8 into the recess 9 when the flexible element 15 urges the member toward the stick 2 or toward the recess 9.

45 The member 21 shown in Figs. 4, 5 and 7 has a ring-shaped part 24 which surrounds the stick 2, contacts the stop 8 and is movable in substan-

tially lateral direction. In this modification, the opening 13 and the stop 8 are opposite to each other with respect to the axis of the stick 2. The member 21 presses the stop 8 into the recess 9 when the flexible element 25 urges the side wall of the opening 13 in a direction pointing away from the stick 2.

The element 15 or 25 may be a chain or another similarly flexible element, for example, a rope, a wire or a band. This chain-like element engages the member 11 or 21 operatively as described before and, in addition, serves to operate a hoisting device which allows to lift and to lower the collar 5. This hoisting device may comprise, in addition to the chain-like element, one or more pulleys and constitutes a movable connection between the collar 5 and the stick 2.

For example, the embodiment shown in Figs. 1 to 3 comprises a pulley 16 which is rotatably carried by the stick 2 and may have a shaft 17 crossing a slot 18 of the stick's upper part. An about U-shaped piece 19 has its legs affixed to the collar 5 and extends therefrom in obliquely upward direction. One end 22 of the element 15 is affixed to the piece 19. From this end, the element extends upwardly, runs over the pulley 16 and further down through the opening 13 and as far as the other end of the element 15 which may terminate in a handle 20.

The pulley 16 guides the element 15 so that the latter can be conveniently pulled or operated from a low point, for example, by the handle 20. The operation may be further facilitated by using a hoisting device which reduces the hand force required for lifting the collar and the awning. For example, the modification illustrated by Figs. 4 and 5 comprises a tackle having a plurality of pulleys. One of these pulleys may be identical to the pulley 16 shown in Figs. 2 and 3, may be identically carried by a shaft 17 and may be identically inserted in a slot 18 of the stick 2. Another pulley 23 is rotatably carried by a shaft 26. This shaft is affixed to two arms 27 which are affixed to the collar 5 in a manner similar to the legs of the piece 19 whereby the pulley 23 is rotatably connected to this collar. One end of the flexible element 25 is affixed to a projection 28 of the stick 2. Therefrom the element 25 extends down, runs over the pulley 23, then up and over the pulley 16 and further down through the opening 13 in a manner similar to the corresponding part of the element 15.

Figs. 2 and 3 show one pulley and a fork-shaped member 15. Figs. 4 and 5 show two pulleys and a ring-shaped member 21. However, the ring-shaped member may be used in an embodiment having only one pulley, and the fork-shaped member may be used in an embodiment comprising a plurality of pulleys.

I desire it understood that my invention is not confined to the particular embodiments shown and described, the same being merely illustrative, and that my invention may be carried out in other ways without departing from the spirit of my invention as it is obvious that the particular embodiments shown and described are only a few of the many that may be employed to attain the objects of my invention.

Having described the nature of my invention, what I claim and desire to protect by Letters Patent is:

1. A garden and beach umbrella comprising a foldable awning, a vertical stick supporting said awning, means spreading said awning and com-

prising a collar slidable along said stick, a resilient stop connected to said stick and normally extending outwardly into a position where said stop prevents said collar from sliding down, a member rockably connected to said collar and engageable with said stop in a direction towards said stick for depressing said stop against the latter to release said collar, said member having an opening, a pulley rotatably connected to said stick and positioned over said collar, and a flexible element extending from said collar over said pulley and then downwardly through said opening in said rockable member.

2. A garden and beach umbrella comprising a foldable awning, a vertical stick supporting said awning, means spreading said awning and comprising a collar slidable along said stick, a stop movably connected to said stick and having an end normally positioned in the path of said collar whereby said stop prevents said collar from sliding down, a member movably connected to said collar and engaging said stop in a direction leading said stop out of the path of said collar, a plurality of pulleys, one of which is rotatably connected to said stick and one of which is rotatably connected to said collar, and a flexible element affixed to said stick, trained over said pulleys and operatively engaging said member.

3. A garden and beach umbrella comprising a foldable awning, a vertical stick supporting said awning and having a lateral recess, means spreading said awning and comprising a collar slidable along said stick, a stop resiliently connected to said stick pressable into said recess and normally extending out of said recess into a position where said stop prevents said collar from sliding down, a member rockably connected to said collar, having a ring-shaped part surrounding said stick and said stop and having an opening positioned oppositely to said stop with respect to said stick, and a hoisting device movably connecting said collar and said stick and comprising a flexible element passing slidably through said opening.

4. A garden and beach umbrella comprising a foldable awning, a vertical stick supporting said awning, means spreading said awning including a collar slidable along said stick, a recess formed in said stick, a resilient stop normally extending out of said recess and engageable with said collar for limiting the downward movement of the latter, a member rockably mounted on said collar and engageable with said stop for depressing the latter into said recess thereby releasing said collar for movement along said stick, pulley means carried by said stick substantially above said stop, and a flexible operating element trained over said pulley means and having one run thereof engaging said collar and the other run thereof slidably extending through said rockable member whereby the exertion of a vertical pull on said operating element will effect movement of said collar along said stick, and the exertion of a horizontal pull on said element will effect rocking of said member for depressing said stop to collar releasing position.

5. A garden and beach umbrella comprising a foldable awning, a vertical stick supporting said awning, means spreading said awning and including a collar slidable along said stick, a resilient stop extending outwardly from said stick into a position where said stop prevents said collar from sliding down, a member rockably connected to said collar and engageable with said stop for pressing the latter against said stick to thereby

release said collar, said member having an opening, and hoisting means movably connecting said collar and said stick and including a flexible operating element engaging said collar and extending from said engagement upwardly and then downwardly through said opening in said rockable member.

6. A garden and beach umbrella comprising a foldable awning, a vertical stick supporting said awning and having a lateral recess, means spreading said awning and including a collar slidable along said stick, a resilient stop connected to said stick and extending outwardly thereof for engagement with said collar to prevent downward movement of the latter, said stop being deformable into said recess for releasing said collar, a horizontally rockable member mounted on said collar and contacting said stop in a direction in which said member presses said stop into said recess, said member having an opening, and a 20

hoisting device connecting said stick and said collar and including a flexible operating element engaging said collar and extending from said engagement upwardly and then downwardly through said opening of said rockable member.
